UNITED STATES PATENT OFFICE.

WILLIAM S. MOSES, OF ONAMIA, MINNESOTA.

INSTRUMENT FOR THE SURVEY AND SOLUTION OF PLANE TRIANGLES IN FIELD WORK.

Application filed August 22, 1921. Serial No. 494,200.

To all whom it may concern:

Be it known that I, WILLIAM S. MOSES, a citizen of the United States, residing at Onamia, in the county of Mille Lacs and 5 State of Minnesota, have invented a new and useful Instrument for the Survey and Solution of Plane Triangles in Field Work, of which the following is a specification.

This invention relates to a new and improved 10 means for finding a numerical ratio triangle for the solution of trigonometric problems comprehended by the art of surveying or for the survey and solution of all plane triangles in field work.

An object of this invention is to provide 15 an instrument for determining the numerical values of the angles and sides of a triangle through a similar triangle whose angles are equal and its sides proportionate 20 to said triangle, the construction of the numerical unit triangle being determined by the positioning of certain elements of the instrument with respect to the similar position 25 of the lines and angles forming the triangle which it is attempted to compute.

The invention will be best understood 30 from a consideration of the following detailed description taken in connection with the accompanying drawing forming part of this specification, with the understanding, however, that the invention is not confined to any strict conformity with the showing in the drawing, but may be changed and modified so long as such changes and modifications 35 mark no material departure from the salient features of the invention as expressed in the appended claims.

In the drawing:—

- Fig. 1 is a side elevation of the device.
- 40 Fig. 2 is a plan view of the same.
- Fig. 3 is a transverse section taken along the line 3—3 of Fig. 2.
- Fig. 4 is a transverse section taken along the line 4—4 of Fig. 2.
- 45 Figs. 5, 6 and 7 represent diagrammatic views of the various positions of the pivoted arms of the instrument and the unit base line.
- In the drawings, 1 designates a tripod for 50 supporting the instrument provided with a table 2 having an upstanding boss 3 which

is perforated. A rotatable disk 4 has a depending pin 5 inserted in the perforation in the boss, the pin being engaged by one end of a set screw 6 to prevent rotation of the 55 pin.

The rotatable disk 4 has an upstanding perforated lug 7 which is engaged upon opposite sides by perforated ears 8 depending from a disk 9. A pin 10 having a threaded 60 portion passes through the aligned perforations of the ears 8 and the lug 7 and is provided with a wing nut 11 adapted to be screwed upon the threaded end of the pin to securely hold the disk 9 in adjusted relation with the rotatable disk 4. Mounted centrally upon the disk 9 is a pin 12 secured in the bottom of a base-line bar 13. An eye-sight 14 and an object sight 15 are located upon opposite ends of the base bar. 70

The base-line bar 13 is provided with a central horizontal line 16 placed upon one side of the bar which forms the base of a numerical unit triangle presently to be described and designated more particularly 75 throughout the specification as the radix. A leveling tube 17 is secured in a socket located in the base bar. The central portion of the tube which is designated by the numeral 18, is disposed in a vertical line passing 80 through the center of the instrument and is adapted to determine the horizontal level of the base-line bar 13 and likewise the radix 16. A handle 19, secured to one end of the bar 13 and at the sighting end of the 85 instrument, is adapted to rotate or tilt the bar when the wing nut 11 is loosened, for positioning the instrument in a horizontal, oblique or vertical plane.

Firmly secured to a vertical side of the 90 bar 13 are two protractors 20 and 21, the centers of which fall upon the ends of the radix or base of the unit triangle. A graduated arm 22, designated at the secant arm, is pivotally mounted on the bar 13, at 95 the center 20^a of the protractor 20 and is secured to a right angle operating rod 23 and spaced from the protractor 20 by means of a washer or shim 24.

A telescope 25 is mounted upon the secant 100 arm 22 by means of the straps 26.

Another graduated arm 27, designated at

the tangent arm, is pivotally mounted on the bar 13 at the center 28 of the protractor 21 and secured to a right angle operating arm 29 which is mounted in bearings in the bar 13. By reason of the washer 24, the arm 27 may be freely oscillated by the sides of the arm 22, and bar 13. Both operating arms 23 and 29 are fitted tightly in their bearings in order to insure against ready displacement of the secant and tangent arms after they have been adjusted.

The inner edge 30 of the arm 27, designated as the tangent ratio line, is adapted to form with the edge 31 of the arm 22 and 15 designated as the secant ratio line, an angle B which is called the angle of limitation. The lines 30 and 31, together with the base line 16, form a numerical ratio triangle which is capable of being made equi-angular 20 with any triangle, the numerical values of the sides and angles of which it is desired to compute, employing the base or radix 16 as a unit line and which is divided into ten equal parts. The arms 22 and 27 are 25 similarly graduated by means of the same scale, each tenth part being divided into tenths and hundredths, thus graduating a unit decimals into tenths, hundredths and thousandths.

30 Another telescope 32 is secured by means of straps 33 to the base bar 13, and it will be seen that when the secant arm 22 has its secant ratio line 31 in alinement with the base or radix, that the telescopes 25 and 32 will be in the same horizontal plane, and furthermore that when the arm 22 is oscillated upwardly and away from the line 16, the telescope 25 will be oscillated and form an angle with the telescope 32, while the 40 arm 22 passing over the protractor 20 will determine the numerical value of the angle between the telescopes 25 and 32, and likewise between the radix and the secant ratio line 31. This angle, represented by A, is 45 designated as the secant angle in Figs. 1, 5 and 6. When the arm 27 is oscillated above or beneath the radix 16, the tangent ratio line 30 will form, with the radix 16, an angle designated as the tangent angle 50 and represented by C, the numerical value of which may be read upon the protractor 21. The angle B formed by the intersection of the tangent ratio line 31 and the secant ratio line 30, forms the angle of limitation 55 of the triangle and is determined by adding angles A and C and subtracting the sum from 180° , or $180^\circ - (A+C) = B$.

The secant arm 22 is provided with the eye-sight 34 and the object sight 35.

60 The telescope 32 is provided with the eye piece 36 while the telescope 25 is provided with eye-piece 37.

The graduated semi-circular part of protractor 21 located above radix line 16 is

adapted for reading angles less than 180° , 65 that are formed by the radix and the tangent ratio line above the radix, while the graduated semi-circular part of the protractor below the radix is adapted for reading angles formed by the tangent ratio line and the radix when tangent arm 27 is rotated below the radix line.

Likewise, the protractor 20 is employed in reading angles formed by the radix and the secant ratio line when the secant arm 75 is oscillated upon its pivot point 20^a, either above or below the radix line 16.

In solving problems relating to triangles, 15 any one of the various fundamental theorems of geometry may be illustrated and a 80 few of them will suffice to demonstrate the application of my device.

If the two angles and a side of a triangle be given, the other angle and the other two sides, 85 may be readily determined in the following manner:—

In Fig. 5, let $AB'C'$ be any triangle, the angles A and C' and the side AC' being given.

To find angle B' and sides AB' and 90 $B'C'$ by means of the ratio triangle ABC of Figs. 1 and 5 formed by base line 16, secant line 31 and tangent line 30, in the following manner:—

Rotate 22 until the secant angle A equals 95 A of the triangle. Also rotate tangent arm 27 until the tangent angle C equals angle C' of Fig. 5.

The angle of limitation B of Fig. 1 is equal to the angle B' of Fig. 5. Since two 100 angles of a triangle are equal to two angles of another triangle, the third angles are equal respectively to each other.

In the unit or ratio triangle shown in Fig. 1, line 16 being a unit and also proportional to the side AC' will bear the following ratio to lines 30 and 31, respectively, of Fig. 1. Therefore, we will have the following formulas from the triangles ABC of Fig. 1 and 5. 110

$$\frac{AB'}{AC'} = \text{secant ratio line};$$

$$\frac{B'C'}{AC'} = \text{tangent ratio line}. \quad 115$$

Suppose, for instance, that the known side AC' , Fig. 5, is equal to 100 feet, and as the line 16 of the ratio triangle in Fig. 1 is a unit line, and the length of the line 31 between the point 20^a and the intersection of the line with the line 30 of the arm 22, designated as AB, is read as $6\frac{1}{2}$ (that is $6\frac{1}{2}$ tenths of unit line 16), line AB' of the similar triangle $AB'C'$ would be equal to 65 120 feet. The length of the line BC on arm 27 between the point 28, and the point where the line 31 cuts the line 30 is read as 4.9, the 125

line BC will be 49 hundredths of the unit line 16, and therefore the side B'C' of the triangle AB'C' would be equal to 49 feet.

Any triangle may be computed through 5 the numerical ratio triangle shown in Fig. 1, when certain parts of the triangle are given, as, when

A side and two angles are given, and when

10 Two sides and the included angle, or opposite angles are given.

Also when the three sides are given.

For surveying and the solution of triangles in field work, telescope 32 is mounted 15 on the base-line bar 13 having its line of sight parallel with the radix or unit base-line 16.

The telescope 25 is mounted on the secant arm 22, having its line of sight parallel 20 with the secant ratio line 31. The sight line of each telescope being equally spaced respectively from the unit base line 16 and the secant ratio line 31, thereby producing two triangles which have two of their 25 respective sides in coincidence and the third side paralleled. Therefore, their angles are equi-angular and their homologous sides proportional.

In sighting the angles formed by the telescopes, or by the sights 14 and 15, and the sights 35 and 34, the angle formed by the intersection of the respective sight lines is called the angle of sight and this angle is placed over the point or station popularly 30 known as the sight station and from which the survey is to be made. After the sight station has been located, the first step is to measure a side and locate an angle between that side and some unknown side 40 which is necessary in the solution of triangles in surveying.

It will be noted that the line of sight through the eye sight 14 and the object sight 15 is so placed on the base line bar 13 that 45 it will be found to be at one side of and parallel with the radix line 16 for determining the position of the radial line of sight. Likewise, the sights 34 and 35 are so positioned on the secant arm 22 that their line 50 of sight will also be to one side and parallel with the secant ratio line 31 for determining the position of the arm 22, or more particularly the secant ratio line 31 or secant angle A.

55 It may further be stated that the sights 14, 15 and 34, 35 may be used jointly with the telescopes, or independently thereof.

Referring to Fig. 6 of the drawings, D 60 designates the ordinary staff used in surveying and which is accordingly graduated and supplied with the vanes B' and C', the base d of the staff resting upon the ground.

The instrument is located at the sight station A, while the staff D is located at a

point distant from the sight station. The 65 distance between the staff D and the sight station A is a line of the triangle A, B', C', which is required to be determined and which may be accomplished in the following manner:—

The instrument illustrated in Fig. 1 is located at the sight station A, and by means of the leveling instrument 17, the base-line bar 13 is horizontally positioned, and by means of the sights 14 and 15 and telescope 70 75 32, the horizontal line AC' which is an extension of the line AC, is determined. The line AC' cuts the staff D as indicated by the vane C'. The secant arm 22 is then rotated by means of the arm 23 and by means of the telescopes and the sights 35, 34, the angle between the secant ratio line 31 and the unit base line 16 is determined, so that an extension of the line 31 will pass through 80 the highest point of the staff D which is 85 located at B' forming the line AB'.

The line B' C' on the staff being known, and which is say 10 feet, it will be easy to find the length of the line AC' by means 90 of the formulas just given which are applicable to the ratio triangle ABC. Lines BC and B' C' are perpendicular to the horizontal line AC', and therefore the tangent arm 27 will be located perpendicularly to the unit base line 16. Since B' C' is the 95 sight tangent, BC the tangent ratio line, AC the unit base line and AC' the line to be determined, the numerical value of the line AC' is found as follows:—

Reading the dimensions from the ratio 100 triangle we have,

$$\begin{aligned} AC &= 1 \\ BC &= 1/100. \end{aligned}$$

Then, since $\frac{BC}{AC} = \text{tangent ratio line}$ and $\frac{B'C'}{AC'} = \text{likewise the tangent ratio line.}$

Tangent ratio line = 1/100.

Now since BC divided by tangent ratio line = AC and also B'C' divided by tangent ratio line = AC', substituting the value of tangent ratio line which is 1/100 in the last formula, we have 10 divided by 1/100 = AC' 110 or AC' = 1000 ft.

Referring to Figs 1 and 7 of the drawings, we illustrate the method of solving a sight triangle.

In Fig. 1, let AB and AC be the sight 120 lines and BC the third side of the ratio triangle.

Let A be the sight station. From the sight station A, sight the radix line 16 on the base line bar 13 to station or angle C', the line AC' passing through C. Sight the secant line AB to angle B'. The angle A is read from protractor 20.

Now measure angle C. Angle B which

is the angle of limitation is determined by the position of lines AB and BC. This completes the ratio triangle, making the ratio triangle and the triangle to be determined equi-angular. The following solution is appropriate:—

The side A'C' is measured, (Fig. 7).
To find B'C' and A'B'

10       $A'C' \text{ times tangent ratio} = B'C'$
 $A'C' \text{ times secant ratio} = A'B'$

Therefore, if A'C' is known, B'C' may be readily found by reading the value of the tangent line BC of the ratio triangle of the instrument and that number multiplied by the base A'C' will give the length of the side B'C'. A'B' may be found in the same manner.

20   What is claimed is:—

1. A surveying instrument comprising, in combination, a base-line bar, graduated arms pivotally mounted at spaced fixed points on the base-line bar, the distance between said points representing a unit base of a numerical triangle, the other two sides of the triangle being formed by the adjacent edges of the pivoted arms, means for rotating the pivoted arms, and telescopes one of which is collimated with the base-line bar and the other with a pivoted arm.

2. A surveying instrument comprising, in combination, a base-line bar, graduated arms pivotally mounted at spaced fixed points on the base-line bar, the distance between said points representing a unit base of a numerical triangle, the other two sides of the triangle being formed by the adjacent graduated edges of the pivoted arms, means for rotating the pivoted arms, and telescopes collimated with the base-line bar and with one of the pivoted arms, one of said telescopes adapted to be positioned at an angle to the other telescope.

3. A surveying instrument comprising, in combination, a base-line bar, graduated arms pivotally mounted at spaced fixed points on the base-line bar and normally rotatable in a vertical or oblique plane, the distance between said points representing a unit base of a triangle, the other two sides of the triangle being formed by the adjacent edges of the pivoted arms, means for rotating the pivoted arms, telescopes collimated with the base-line bar and with one of the pivoted arms, and sight means located on one of the pivoted means and on the base-line bar, the sight means and a telescope forming equal angles with a line passing centrally of the base-line bar at all positions of one of the arms.

4. A surveying instrument comprising, in combination, a base-line bar, graduated arms pivotally mounted at spaced fixed

points on the base-line bar and normally rotatable in any plane, the distance between said points representing a unit base of a triangle, the other two sides of the triangle being formed by the adjacent edges of the pivoted arms, means for rotating the pivoted arms, and sight means located on one of the pivoted means and on the base-line bar, the lines of sight through said sight means being collimated with two sides of the triangle to determine the sight angles of the triangle.

5. A surveying instrument comprising, in combination, a base-line bar graduated arms pivotally mounted at spaced fixed points on the base-line bar and normally rotatable in a vertical or other plane, the distance between the fixed points representing a unit base of a triangle, the other two sides of the triangle being formed by the adjacent edges of the pivoted arms, telescopes collimated with the base-line bar and with one of the pivoted arms, and sight means located on one of the pivoted means and on the base-line bar, said telescopes and sight means being respectively located normally in the same horizontal planes.

6. A surveying instrument comprising, in combination, a base-line bar graduated arms pivotally mounted at spaced fixed points on the base-line bar and normally rotatable in a vertical plane, the distance between said points representing a unit base of a triangle, the other two sides of the triangle being formed by the adjacent edges of the pivoted arms, means for rotating the pivoted arms, telescopes collimated with the base-line bar and with one of the pivoted arms, sight means located on one of the pivoted means and on the base-line bar, the sight means being in alinement with the pivotal points of the oscillating arms, and means for alining one edge of a pivoted arm with a line passing through the sight means and the pivotal points of the arms.

7. In a surveying instrument comprising a base bar provided with a base line, means for determining the horizontal position of the line, graduated arms pivotally mounted at spaced fixed points on the line, the distance between said points representing the unit base of a triangle, the other two sides of the triangle being formed by the adjacent edges of the pivoted arms and the length of the sides of the triangle being determined by the intersection of said pivoted arms, one of said arms adapted to be positioned perpendicular to the base line, the other arm forming an acute angle with the base line, and sighting means on the base bar and arranged in a plane passing through the base line.

8. A surveying instrument comprising,

in combination, a base-line bar graduated arms pivotally mounted at spaced fixed points on the base-line bar, the distance between said points representing a unit base of a numerical triangle, the other two sides of the triangle being formed by the adjacent edges of the pivoted arms, means for rotating the pivoted arms, and telescopes

one of which is collimated with the base-line bar and the other with a pivoted arm, **10** and means for adjustably supporting the instrument.

In testimony, that I claim the foregoing as my own, I have hereto affixed my signature.

WILLIAM S. MOSES.
